CONNECTING PLATE FOR RAIL JOINTS

Filed April 11, 1924

SAM SORENSEN, Inventor

By *Jesse R. Stone*

his Attorney

UNITED STATES PATENT OFFICE.

SAM SORENSEN, OF HOUSTON, TEXAS.

CONNECTING PLATE FOR RAIL JOINTS.

Application filed April 11, 1924. Serial No. 705,769.

To all whom it may concern:

Be it known that I, SAM SORENSEN, a citizen of the United States, residing at Houston, Texas, have invented a certain new and useful Improvement in Connecting Plates for Rail Joints, of which the following is a specification.

My invention relates to the construction of plates for connecting and bracing the joints of rails on railway tracks.

In the laying of rails in the construction of railways, it is common to connect adjacent rails by fish plates secured to the rail ends by bolts extending through the said plates and rails. Such bolts are liable to longitudinal stretching and distortion due to the strain of traffic and the rails may be thus loosened to such an extent as to be unsafe.

It is an object of the invention to provide means to connect the ends of the rails in such manner as to take the strain from the bolts, thus preventing their becoming loosened. This is done by a base plate formed to cooperate with the fish plates connecting the rails so as to hold the said fish plates clamped to the rails.

It is also desired to construct a device of this character which is easily applied and economical to construct.

In the drawings herewith I have shown a preferred form of my invention, in which Fig. 1 shows a top plan view of the invention applied to two rail ends. Fig. 2 is a side elevation thereof. Fig. 3 is a transverse section on the plane 3-3 of Fig. 2; and Fig. 4 is a similar view on the plane 4-4 of Fig. 2. Like numerals of reference are applied to like parts in all the views.

The fish plates 3, 3, employed in connecting the ends of rails 1 together, are made in the form of a heavy angle iron as is customary. The upright portion 3 of the plate fits beneath the lower side of the rail top, while the lower horizontal portion 4 rests upon the base 5 of the rail. Said base portion is extended beyond the rail base at spaced points forming lugs or tongues 6, perforated to receive cap screws 7.

The tongues 6 are adapted to fit within notches or recesses 8 in a base plate 9 upon which the rail rests. The said plate is of the same length as the fish plates. It has

a central longitudinal seat 10 for the rail base with lateral upstanding flanges 11, 11 at each side fitting the rail base closely to prevent lateral displacement of the rails. The flanges 11, 11 are formed with recesses 8, as previously described, to receive the cooperating tongues 6 on the fish plates. 60

The inner upper sides of the flanges 11, 11 are beveled slightly at 12 to allow a wedging fit with the fish plates. The tongues 6 and the recesses in which they fit are also tapered in width outwardly for ease 65 in assembly and for the better fitting of the parts to prevent relative movement.

The fish plates are secured to the rail ends by bolts 13 in the usual manner. The cap screws 7, by means of which the fish 70 plate is secured to the base plate, are of sufficient length to extend part way through the base plate, as shown in Fig. 3. It will be noted that the plates are adapted to fit the rail closely and that the fish plates also 75 interfit tightly with the base plate. In this manner the plates form a rigid support allowing no perceptible play between the parts and preventing lateral or vertical displacement. There is, therefore, no heavy 80 strain or pull upon the tie bolts 13 as is customary.

The combination of the base plate with the fish plates is particularly strong and rigid. The attachment is easily and conveniently made and at a reasonable cost. 85 Further objects and advantages will be clear to one skilled in the art without further description.

What I claim as new and desire to protect by Letters Patent is:

1. In a device of the character described, a rail base plate shaped to receive the rails, fish plates, tongues on said fish plates fitting within recesses in said base plate and cap screws extending through said tongues into said base plate.

2. In a device of the character described, a rail base plate to support the rail ends, lateral flanges on the sides of said seat said 100 sides beveled to converge downwardly and having spaced notches cut therein, fish plates, tongues on said fish plates fitting in said notches, and screws securing said fish plates within said tapered seat at the sides 105 of said rail.

2

3. In a device of the character described, a rail base plate to support the adjacent rail ends, lateral flanges on said plate at each side of the rails, the inner faces thereof converging downwardly and having spaced notches therein, fish plates having lugs fitting in said notches, and shaped to be clamped between the top and base of the rail and means to secure said fish plates to said base plate at the side of the rail. ¹⁰

In testimony whereof I hereunto affix my signature this 8th day of April, A. D. 1924.

SAM SORENSEN.
